FRAME FOR A DISPLAY SIGN

Lindell N. Edwards, St. Louis, Mo., assignor to Commander Board International, Inc., St. Louis, Mo., a corporation of Missouri

Filed Aug. 24, 1966, Ser. No. 3,573

Term of patent 14 years

(Cl. D1—12)

FIG. 1.

FIG. 2.

FIG. 3.

FIGURE 1 is an elevational view of a frame for a display sign embodying my new design with portions broken away to indicate indeterminate width and height;

The fragmentary broken line representation of a sign panel in FIGURES 1 and 2 is for purposes of illustration only.

I claim:

The ornamental design for a frame for a display sign, as shown and described.
